UNITED STATES PATENT OFFICE

ERNEST H. HOLZWORTH, OF BUFFALO, NEW YORK

TUYÈRE FOR BLAST FURNACES

Application filed May 17, 1927. Serial No. 191,950.

This invention relates to improvements in the tuyères used in connection with blast furnaces.

One of its objects is the provision of a tuyère having novel means for the circulation of a cooling fluid around the nose end of the tuyère to enable the same to withstand the high temperatures present in blast furnaces.

10 Another object of the invention is to provide a water cooled tuyère which is so constructed as to provide a maximum cooling effect at the nose end of the tuyère and thus prolong its life.

15 A still further object is to provide a tuyère of this character which is simple and inexpensive in construction, which is efficient in operation and which will materially reduce the maintenance costs of blast furnaces.

20 In the accompanying drawings: Figure 1 is a top plan view of a tuyère embodying my invention. Figure 2 is a vertical longitudinal section taken on line 2—2, Figure 1. Figure 3 is a transverse section on line 3—3, 25 Figure 2. Figure 4 is a detached perspective view of the circulating coil or conduit.

Similar characters of reference indicate corresponding parts throughout the several views.

30 The improved tuyère consists of a substantially frusto-conical body 10 made of a copper alloy or other appropriate material and having the usual passage 11 for the admission of air to the furnace, this passage being 35 connected at its base or outer end with the source of air supply by a pipe 12. The tuyère-body has a cooling chamber or compartment 13 surrounding its air passage which extends from the base of said body to

40 a point short of its inner or nose end, as shown in Figure 2. Disposed in the nose end of the tuyère is a second cooling compartment which preferably consists of a coil 14 of steel pipe or the like encased or embedded 45 within the tuyère-body and having an inlet branch or conduit 15 extending lengthwise thru the compartment 13 and connected to a water supply pipe 16. This coil also has an outlet branch 17 connected therewith 50 which may be parallel with the companion

inlet branch 15, as shown in Figures 1 and 4, and which preferably discharges into the inner end of the compartment 13. The nose end of the tuyère-body is thickened, as shown, and the coil is cast therein, so that it is 55 isolated and separate from the main circulating compartment. Connected to the outer end of the tuyère-body is a discharge pipe 18 thru which the water or other cooling fluid is passed after being circulated first thru the coil 14 and then thru the compartment 13.

60 By this construction the cold water is delivered directly to the coil 14 encased in the nose end of the tuyère where the maximum cooling is required. While this coil is preferably made of a steel pipe it is to be understood that the same may be made of any other suitable material which has a higher melting point than that of the tuyère-body. The location of coil in the nose end of the tuyère 65 and its isolation from the compartment 13 keeps the temperature at the nose to a minimum and materially reduces the possibility of its burning off. Furthermore, the provision of coil arranged as shown insures a constant circulation of the water under pressure in a defined course of travel, the coldest part of the water being delivered to the hottest part of the tuyère with the result that all portions of the nose are kept at a substantially 70 even temperature and danger of cracking or breaking of the tuyère due to uneven expansion and contraction is thereby eliminated.

75 It will be noted that the cross-sectional area of the coil 14, together with its branches 15 and 17, is approximately the same as that of the water supply pipe 16, so that the water is caused to circulate at a uniform velocity thru the coil.

80 I claim as my invention:—

85 A blast furnace tuyère, comprising a body having an air passage extending therethrough and a water-circulating compartment surrounding said air passage and extending from the base to a point short of the nose of said body, and a circulating coil embedded in the nose and isolated from said compartment, said coil having an inlet branch 90 extending lengthwise through the water-circulating compartment for deliver- 95

ing a continuous supply of water through the coil and an outlet branch disposed substantially parallel with said inlet branch and discharging into the inner end of said compartment, the coil being made of a material having a higher melting point than that of the tuyère-body.
